UNITED STATES PATENT OFFICE.

WILLIAM A. BROWN, OF NEW YORK, N. Y.

DESIGN FOR A SPOON.

SPECIFICATION forming part of Design No. 29,661, dated November 15, 1898.

Application filed September 30, 1898. Serial No. 692,344. Term of patent 3½ years.

To all whom it may concern:

Be it known that I, WILLIAM A. BROWN, a citizen of the United States, residing in New York city, in the county of New York, State of New York, have invented and produced a certain new and useful Design for Spoons; and I do hereby declare the following to be a full, clear, and exact description of the invention, such as will enable others skilled in the art to which it appertains to make and use the same.

My invention consists in the design for spoons illustrated in the accompanying drawings and described in the following specification.

In the drawings, Figure 1 is an elevation of the obverse of the spoon, and Fig. 2 is a similar view of the reverse of the same.

As shown in Fig. 1, the central portion of the bowl of the spoon is occupied by a three-quarters bas-relief portrait *a*, intended to represent Theodore Roosevelt, lieutenant-colonel of the troop of United States Volunteers known in the Spanish-American war as "Rough Riders," Colonel Roosevelt appearing in the portrait as in army uniform and hat. This portion is inclosed on either side of the lower part by an ornamental wreath *b*, consisting of a laurel branch *b'* on one side and a spray or branch of oak-leaves *b''* on the other side, the stems of the two branches being tied together beneath the portrait by a knotted ribbon *c* and extended up along the edges of the bowl about half-way of its length. In the upper part of the bowl is a flowing ribbon *d*, the same being represented as tied in a loose knot *e* around the shank of the handle and as falling in graceful festoons downwardly along the edges of the bowl on either side of the portrait and, together with the oak and laurel branches above described, completing the inclosing setting for the portrait. The upper part of the handle of the spoon contains in bas-relief the figure of a cavalryman *f* of the troop of Rough Riders, the horse *g*, on which he is mounted, appearing as in a full gallop, coming head-on toward the observer. In his

right hand the trooper carries a United States flag *h*, the staff resting in a socket at the stirrup and the fold of the flag forming the outer edge of enlarged part of the handle on one side. On the opposite edge of this part of the handle there is a scroll *i*, represented as rising from behind the trooper and extending upward to the end of the handle, where it has a small festoon *i'*, joining the upper end of the flagstaff. Accompanying this scroll is a branch of palms *j*, its upper portion bending gracefully toward the center of the handle over the trooper's head.

The reverse side of the spoon is ornamented as represented in Fig. 2. The bowl is plain, except that the ribbon out of which the knot *e* of the reverse side is formed shows at *e*, and there is a small leaf-like ornamentation *k* just below the ribbon. The handle contains a decorative arrangement of palm branches or leaves *l*, running up along each edge, combined with a scroll or ribbon *i''*, which is represented as wound around the handle and binding the palm branches together. The upward extension of these palm branches along the edges of the enlarged part of the handle forms an ornamental setting or frame for a portrait *m* of a Rough Rider dismounted and in the act of firing his carbine, the trooper being represented as kneeling and resting the elbow of the arm supporting the gun on his knee.

Having thus described my design, what I claim is—

1. In the design for a spoon, the obverse, substantially as herein shown and described.
2. In the design for a spoon, the reverse, substantially as herein shown and described.
3. The design for a spoon substantially as herein shown and described.

In testimony whereof I affix my signature in presence of two witnesses.

WILLIAM A. BROWN.

Witnesses:

WILLIAM E. WARD,
SUSAN BRANDENBURG.
